UNITED STATES PATENT OFFICE.

MOSES HEIMANN, OF BERLIN, GERMANY.

PATTERN-CYLINDER FOR USE IN THE MANUFACTURE OF PAPER LACE AND THE LIKE.

No. 801,522.

Specification of Letters Patent.

Patented Oct. 10, 1905.

Application filed February 29, 1904. Serial No. 195,921.

To all whom it may concern:

Be it known that I, MOSES HEIMANN, a subject of the German Emperor, residing at Berlin, Germany, have invented certain new and 5 useful Improvements in Pattern-Cylinders for Use in the Manufacture of Paper Lace and the Like, of which the following is a specification.

This invention relates to improvements in 10 pattern-cylinders for use in the manufacture of paper lace.

Heretofore for the manufacture of paper lace an engraved untempered-steel pattern-cylinder is usually used, which works in conjunction with a lead cylinder, or an engraved 15 tempered-steel pattern-cylinder is used working in conjunction with a similarly-tempered smooth steel cylinder.

With a tempered engraved pattern-cylinder, which works against a similarly-tempered smooth cylinder, which is of equal hardness, it is impossible to manufacture fine paper lace, because with tempered steel the fine projecting parts of the pattern easily break or 20 do not sufficiently cut out the paper. The cylinders are also often distorted in the tempering, so that their meeting surfaces require to be polished by means of an emery-wheel. In the latter case it frequently occurs that the 25 cylinders cut very badly or that they become quite useless.

The untempered engraved cylinders working against lead cylinders also have the disadvantage that the efficiency of the apparatus 30 is very small, and that the manufacture of paper lace is extremely expensive, owing to the wear of the metals, and, moreover, the frequent polishing and turning cause a great loss of time. Further, the lead-dust produced 35 in the manufacture is very dangerous to health, and lead-poisoning of the workmen has frequently occurred. Another disadvantage is the fact that it is very difficult to print the paper, as owing to the continual wear of the 40 lead cylinder the printing-cylinder does not work in coincidence with the engraved steel cylinder and has to be continually adjusted.

The pattern-cylinders to which this invention relates remove all the above-mentioned 45 disadvantages.

Figure 1 of the annexed drawings is a plan view, and Fig. 2 a section, of the improved cylinders.

With these pattern-cylinders paper lace 50 with large and fine patterns can be manufac-

tured, and the efficiency of the apparatus is much greater than hitherto.

The improvements in the pattern-cylinders consist in the employment in combination of a tempered-steel cylinder *a*, on which the pattern *d* is engraved in relief with an untempered-steel cylinder *b*, originally smooth, but having the pattern *e* impressed deep enough into its surface by the rolling action under pressure of the aforesaid tempered cylinder 60 to insure a uniform cutting of the paper.

At the ends of the tempered cylinder are rings *c* of untempered steel. The aforesaid rings which serve for protecting the raised pattern when the cylinder is not in use are 70 already used in paper-lace machines; but they have hitherto always been of the same degree of hardness as the pattern on the cylinder.

With the improved cylinders the protecting steel rings are untempered, since if tempered they would soon prevent or retard the edges of the pattern from cutting the paper, whereas the untempered rings are malleable enough to be compressed or spread under the pressure of rolling to allow the tempered pattern to engrave itself on the untempered cylinder. 75

With the improved cylinders polishing or setting of the engravings or edges is not necessary, since the lower untempered cylinder 80 fits exactly into the upper engraved cylinder, even if the latter should have become distorted in the tempering.

Contrary to the old system a separate lower cylinder is necessary for each engraved cylinder; but this is a trifling drawback compared with the great advantages obtained and the greater efficiency of the new cylinders. 85

I claim—

The combination of a relief engraved tempered-steel cylinder having a softer untempered-steel ring at each end thereof, and an untempered softer steel cylinder in juxtaposition to said first-mentioned cylinder, on which softer steel cylinder the pattern has 90 been impressed by rotation under pressure against the tempered cylinder for the purpose set forth.

In witness whereof I have signed this specification in the presence of two witnesses.

MOSES HEIMANN.
